FRED L. BETHGE AND JOHN W. STORER, OF DENVER, COLORADO, ASSIGNORS TO
RICHARD M. AITKIN, OF DENVER, COLORADO.

AUXILIARY LOCK FOR BOLTS.

Application filed December 15, 1921. Serial No. 522,629.

To all whom it may concern:

Be it known that we, FRED L. BETHGE and JOHN W. STORER, both citizens of the United States, residing at the city and county of Denver and State of Colorado, have invented certain new and useful Improvements in Auxiliary Locks for Bolts, of which the following is a specification.

This invention relates to improvements in auxiliary burglar-proof protective equipment for locking bolts, and while the invention has been primarily devised with reference to the general bolt shooting systems of permutation-lock controlled safety vault doors, it is to be understood at the outset that the improvements are not necessarily restricted to any such one specific use, but may likewise be satisfactorily employed with other analogous safety bolting systems. It is understood that, in burglarizing vaults, safes and analogous permutation-lock controlled compartments, it is quite customary to disrupt the permutation-lock tumblers, by drilling and punching or by the employment of electricity, an oxy-acetylene torch or explosive forces, to permit of the manipulation of the door bolts. Various devices and systems have accordingly been heretofore devised to automatically bring supplementary locking means into operation in such an emergency, but, without specifically discussing such prior advances in the art, it may be said briefly that there are many serious objections thereto, because such devices or systems themselves as a rule have been susceptible of being tampered with to render them inoperative before attempting to disrupt the permutation lock, the functioning of which disruption was aimed to cause the actuation of said supplementary locking means.

The broader aim of the present invention has been to provide a novelly constructed auxiliary locking device so associated with the door bolts themselves, by a new combination and arrangement of operative connections leading to the zone of the permutation lock, that the auxiliary locking device, although bodily movable normally with the door bolts but in latched set relation, will automatically be caused to itself positively maintain the door bolts locked, if the permutation lock is in any manner disrupted or should the connections leading from the

auxiliary locking device be tampered with prior to the attempted disruption of the main or permutation lock.

The foregoing, however, as well as other objects and advantages including simplicity of construction, efficiency in operation and comparatively small cost of production and installation, will be so clearly apparent as incidental to the following disclosure that it would serve no useful purpose to further enlarge upon the same initially, and with these prefacing remarks, therefore, reference will now be immediately had to the accompanying drawings illustrating a practical embodiment of the improvements, in which drawings like reference characters designate the same parts throughout and in the views of which

Figure 1 is a detail face view of the auxiliary locking device by itself, with its cover plate removed to show the internal elements in their inert withdrawn positions;

Figure 2 is a view analogous to Fig. 1, but with the lock's bolt released and shot to its locking positions;

Figure 3 is a cross-sectional view on the line 3-3 of Figure 1;

Figure 4 is a fragmentary interior elevational view of a vault door with the improvements applied in operatively set position, and with the door bolts free to be moved by the door handle under control of the permutation lock; and

Figure 5 is a view analogous to Fig. 4, but with the auxiliary locking device sprung into effective locking position.

Referring first to Figures 1 to 3, in describing the details of construction of the auxiliary locking device by itself, the numeral 11 designates the lock casing which provides the bolt chamber 12 and a base or lower edge face flange 13, the latter being adapted to be securely fastened to one of the door bolts, as by means of screws or bolts and holes therefor generally indicated at 14, and a cover plate 10 is provided which is adapted to be attached to the front, or otherwise open face of the casing, as by means of screws or bolts and holes therefor generally indicated at 9.

The lower wall of the casing proper is slotted as at 15 to allow for the projection of a detent therethrough, as later referred to, while the upper wall of the casing pro-

vides an aperture 16, also opening to the bolt chamber 12, in which operates a lug 17 pressed downwardly by a flat spring 18 or its equivalent.

5 The bolt chamber 12 is substantially enlarged at its right end and is formed with an abutment shoulder 19 disposed rearwardly of the aperture 16 and above the plane of the forward end of the bolt chamber 12.

10 20 designates the bolt of the auxiliary lock, which bolt has a stepped upper face at its rear end to provide a recess 21, to register with and receive the lower end of 15 the lug 17 when operated, and a limiting offset shoulder 22, or equivalent stop element, for association with the casing abutment shoulder 19. Normally, the lower end face of the lug 17 seats on the top face of the bolt 20, but drops in the recess 21 when the 20 bolt is shot, as will be understood.

The rear or right end of the bolt 20 provides a shank or extension 23, operating in a hollow nipple or projection 24, which hollow projection also partially houses a coiled spring 25 encircling the shank 23, the said coiled spring being so mounted and functioning under tension as to exert a forward constant pressure on the bolt 20.

25 26 designates a latching recess opening downwardly from the bottom face of the bolt 20, which recess 26 is adapted for registration with the slot 15 of the casing to co-operate with the latching tooth or detent 30 35 projecting upwardly from a tripping lever 27 that is pivoted at one end, as at 28, to the flange 13 and which may provide at its other end an eye 29 or other means for the attachment of tripping wires or connections, 40 leading to the zone of the permutation lock and hereinafter referred to.

45 Before specifically describing or referring to the operation and functioning of certain other novel features involved in the present invention, it may be well to first refer briefly to one type of vault door construction, as illustrated at Figures 4 and 5 with our invention applied, in which views 31 designates the inside face of a vault door, with 50 the interior cover plate removed if one is employed. These doors may have marginal ribs 32 apertured to slidably mount the outer ends of laterally projecting door bolts 33-34, coupled at their inner ends by lever 55 arms 35, and vertically disposed door bolts 36 also operatively coupled with the door bolts 33-34, all of which bolts are adapted to be actuated in unison in reverse directions as is understood, although it may not 60 be amiss to briefly describe such operation as follows:—37 designates a vertical bar, bodily movable laterally by the operation of the outside vault door handle, and the door bolts 33 are secured to this bar 37 as 65 by means of screws or bolts 38. The bar 37

also carries a stud or tumbler pin element 39 that operates in association with the tumblers of the combination or permutation lock 40, all of which is understood from the prior art and which in themselves form no 70 feature of the present invention.

As has before been stated, the auxiliary locking device is securely attached to one of the door bolts so as to be bodily movable therewith under normal conditions, and as 75 a matter of convenience we have shown this auxiliary lock as carried by the upper lateral door bolt 33, although by slight rearrangements it could be mounted on another one of the door bolts if desired, but in 80 carrying out the invention an abutment element fixedly mounted on the door should be disposed at such a suitable distance away from the bolt shooting end of the auxiliary lock, in line therewith, so that the lock casting itself will not engage the abutment although allowing for the end of the bolt 20 to engage the abutment element when the auxiliary lock is automatically shot.

85 As a matter of fact, the particular type 90 of vault door illustrated has a central longitudinal rib 41, which is apertured to slidably mount the inner ends of the door bolts 33-34, and where such a central rib is employed it will also serve as the abut- 95 ment element just previously referred to. It is to be understood, however, that we do not limit ourselves to the use of this central rib element 41 as the exact form of said abutment, as a separate lug or any other 100 suitable stop element could be employed to function in an equivalent manner.

42-43 indicate a pair of flexible tripping connections, preferably formed of copper wire, the upper end of each of which is attached to the tripping lever 27, of the auxiliary lock, by means of the aperture 29 or a suspension plate element 44. The wire 43 is reeved around underneath a sheave 45, mounted on a stud pin 46, from whence 110 it is led upwardly and is firmly secured to the lower end of a distended coiled spring 47, or analogous retracting element, which is held under return tension by means of a connection secured at its lower end to the 115 vault door as is indicated at 49, the connection preferably including a copper wire 48 for its upper length, with the lower length embodying a fuse element, as indicated at 50, interposed in the line somewhere near the permutation lock 40 and 120 preferably extending underneath the tumbler pin 39, while 51 indicates a turnbuckle element for tautening up this connecting line to regulate the tension of the spring 47. 125 Obviously, there could be other extensions of the wire 48 with appropriate fuse elements 50 located at other positions if desired, although it is believed that the one fuse located as it is would suffice.

The wire 42 is threaded through an aperture in the stud pin 46, serving as a cotter pin for the sheave 45, from whence it extends to and through a guiding eyelet 52, 5 mounted on the safe door just above the main or permutation lock 40, thence over the back of the permutation lock in the rear of the tumbler zone, and is finally drawn tautly and secured at its lower end to the vault door, as at 53, below the permutation lock.

Operation.

Now, if the auxiliary lock's bolt 20 is set in withdrawn latched position, as is illustrated at Figures 1 and 4, it will be obvious that the vault door bolts may be operated to their locking and unlocking positions, under the legitimate control of the main or permutation lock 40, the auxiliary lock moving freely back and forth with the upper lateral door bolt 33 to which it is fixedly secured; but assuming that the vault door is closed and locked by the door bolts, with the permutation lock 40 set, and that an attempt is made to burglarize the vault by the usual method of dislodging the permutation lock or its tumblers, then the auxiliary locking device will be brought into effective use, 20 with its bolt 20 projected up against the door abutment 41, as will appear from Figure 5 where the dotted circles of the permutation lock indicate that the tumbler elements have been dislodged and the wire 42 25 disrupted, so that the auxiliary locking device now holds the door bolts jammed in their locked position regardless of the disruption of the permutation lock. Of course, from the foregoing it will be understood 30 that we are assuming that the burglar has dislodged the tumbler elements of the main lock by an explosive force or by drilling and punching, which in disrupting the wire 42 gives it a pull or tug that actuates the lever 35 45 27 to release the detent 30 from its latching recess 26, thereby causing the spring 25 to shoot the bolt 20.

However, the burglar is wise and might first drill or burn a hole through the door 50 for the purpose of clipping the connection 42 if it be a wire, or cutting it otherwise if it be a stouter connection, before attempting to disrupt the combination lock, and in that event there would be no pull on the connection 42, which is one of the many objections to many of the auxiliary locks heretofore employed.

By the present improvements we additionally guard against such contingencies by 55 the employment of the auxiliary connections including the elements 43—47—48—50, embodying in the line a fusible section that has substantial tensile strength but which instantly melts in the presence of generated heat. In other words, if a torch were ap-

plied, or even a drill employed, to first get a hole through the door of the vault in proximity to the main lock, the heat generated would melt the fuse 50 and thus relieve the tension of the spring 70 47, which latter would then exert the necessary pull or tug on the wire 43 to trip the lever 27. Furthermore, the connections 48—50, or their equivalent, could be so associated with the permutation lock, that a disruption 75 would occur upon the dislodgment of the latter, whether the disruption was effected by melting or otherwise, when the actuation of the wire 43 would necessarily follow with the same result as before explained.

It is believed that the full advantages of all of the foregoing novel features will be quite apparent, especially when we consider the extreme necessity of taking every precaution to make a vault or the like as burglar-proof as feasible, but while we have thus fully set forth the improvements, it will nevertheless be understood that we do not wish to unnecessarily restrict ourselves to all of the details exactly as disclosed, excepting as they may come within the terms of the ensuing claims, or equivalent elements employed, and as fairly interpreted in the light of the specification if necessary, as it is obvious that minor alterations might be 90 made without departing from the spirit or 95 gist of the invention.

What we do claim as new and patentable is:—

1. In protective systems for the locking bolts of closures, providing a jamming abutment, and which bolts are under the control of a permutation main lock, the combination of an auxiliary locking device mounted in fixed relation to said bolts for bodily movement therewith in the zone of said abutment, a bolt element for said device that is disposed for shooting into engaging association with said abutment, means tending to force said bolt element into its shot position, 100 retaining means for normally holding said bolt element withdrawn, and connecting means leading from said retaining means into the zone of said permutation lock for tripping said retaining means by a dismantling of said connecting means.

2. In protective systems for the locking bolts of closures, providing a jamming abutment, and which bolts are under the control of a permutation main lock, the combination 105 of an auxiliary locking device fixedly carried by one of said bolts for bodily movement therewith in the zone of said abutment, a bolt element for said device that is disposed for shooting into engaging association with said abutment, means tending to force said bolt element into its shot position, 110 retaining means for normally holding said bolt element withdrawn, and connecting means leading from said retaining means 115 for dismantling of said connecting means.

into the zone of said permutation lock for tripping said retaining means by a dismantling of said connecting means.

3. In protective systems for the locking bolts of closures, providing a jamming abutment, and which bolts are under the control of a permutation main lock, the combination of an auxiliary lock fixedly carried by one of said bolts for bodily movement therewith in the zone of said abutment, the said auxiliary lock embodying a bolt, with latching means therefor, disposed under spring tension to be shot into engaging association with said abutment, and connecting means leading from said latching means into the zone of said permutation lock for causing the tripping of said latching means by an unauthorized dismantling action on said connecting means.

4. In protective systems for the locking bolts of closures, providing a jamming abutment, and which bolts are under the control of a permutation main lock, the combination of an auxiliary locking device mounted in fixed relation to said bolts for bodily movement therewith in the zone of said abutment, a bolt element for said device that is disposed for shooting into engaging association with said abutment, means tending to force said bolt element into its shot position, retaining means for normally holding said bolt element withdrawn, and connecting means leading from said retaining means, including a fuse section disposed proximately of said permutation lock, which are so mounted and controlled as to trip said retaining means upon an unauthorized dismantling of said connecting means.

5. In protective systems for the locking bolts of closures, providing a jamming abutment, and which bolts are under the control of a permutation main lock, the combination of an auxiliary locking device mounted in fixed relation to said bolts for bodily movement therewith in the zone of said abutment, a bolt element for said device that is disposed for shooting into engaging association with said abutment, means tending to force said bolt element into its shot position, retaining means for normally holding said bolt element withdrawn, connecting means leading from said retaining means, including a fuse section disposed proximately of said permutation lock, and connecting means leading from said retaining means and anchored at its other end tautly over the rear zone of the tumblers of said permutation lock, both of which said connecting means

function as tripping means for said retaining means, substantially as described.

6. In protective systems for the locking bolts of closures, providing a jamming abutment, and which bolts are under the control of a permutation lock, the combination of an auxiliary locking device mounted in fixed relation to said bolts for bodily movement therewith in the zone of said abutment, a bolt element for said device that is disposed for shooting into engaging association with said abutment, means tending to force said bolt element into its shot position, retaining means for normally holding said bolt element withdrawn, a spring mounted by said closure and having a free end, connecting means leading from the free end of said spring, including a fuse section disposed proximately of said permutation lock, for tautly holding said spring normally under retractile tension, a guiding element associated with said spring, and a flexible connection leading from said retaining means to the free end of said spring by way of said guiding element.

7. In protective systems for the locking bolts of closures, providing a jamming abutment, and which bolts are under the control of a permutation main lock, the combination of an auxiliary locking device mounted in fixed relation to said bolts for bodily movement therewith in the zone of said abutment, a bolt element for said device that is disposed for shooting into engaging association with said abutment, means tending to force said bolt element into its shot position, retaining means for normally holding said bolt element withdrawn, a spring mounted towards one end by said closure, connecting means leading from the free end of said spring, including a fuse section disposed proximately of said permutation lock, for normally holding said spring tautly under retractile tension, a guiding element associated with said spring, a flexible connection leading from said retaining means to the free end of said spring by way of said guiding element, and a separate flexible connection leading from said retaining means and anchored at its other end tautly over said permutation lock at the rear of its tumbler zone, both of which said flexible connections function as tripping means for said retaining means, substantially as described.

In testimony whereof, we affix our signatures.

FRED L. BETHGE,
JOHN W. STORER.
